MEDICINE CABINET

Harry V. Anderson, Encino, Calif.

Application October 10, 1955, Serial No. 38,300

Term of patent 14 years

(Cl. D4—3)

Fig. 1.

Fig. 2.

Fig. 3.

Fig. 4.

Fig. 1 is a perspective view of a medicine cabinet, shown with doors closed, showing my new design;

Fig. 2 is a perspective view of the cabinet with doors open;

Fig. 3 is a front view of the cabinet; and

Fig. 4 is a side view of the cabinet.

The characteristic feature of the medicine cabinet disclosed resides in the light casing atop the cabinet having the configuration shown.

I claim:

The ornamental design for a medicine cabinet, as shown and described.
